Specification for Design.

Patented Dec. 28, 1920.

Application filed August 5, 1920. Serial No. 401,524. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for an Arm for a Lighting-Fixture, of which the following is a specification, reference being had

to the accompanying drawing, forming part thereof.

The single figure of the drawing is a perspective view of an arm for a lighting fixture, showing our new design.

We claim:

The ornamental design for an arm for a lighting fixture, as shown.

GEORGE V. STRAHAN.
FREDERICK W. MATHIEU.
